ROBERT O. FLOCKE, OF NEWARK, NEW JERSEY, ASSIGNOR TO THE R. NEUMANN HARDWARE CO., A CORPORATION OF NEW JERSEY.

LOCKING-CATCH FOR PORTFOLIOS AND THE LIKE.

1,267,650.

Specification of Letters Patent.

Patented May 28, 1918.

Application filed February 9, 1918. Serial No. 216,143.

To all whom it may concern:

Be it known that I, ROBERT O. FLOCKE, a citizen of the United States, residing at Newark, in the county of Essex and State 5 of New Jersey, have invented certain new and useful Improvements in Locking-Catches for Portfolios, and the like; and I do hereby declare the following to be a full, clear, and exact description of the invention, 10 such as will enable others skilled in the art to which it appertains to make and use the same, reference being had to the accompanying drawings, and to characters of reference marked thereon, which form a part of this 15 specification.

This invention relates, generally, to improvements in catches; and, the present invention has reference, more particularly, to a novel form of locking or holding catch 20 which is especially adapted for use with portfolios, music rolls, and the like.

The present invention has for its principal object to provide a novel and simply constructed locking or holding catch of the 25 general character and construction herein-after more particularly set forth, and one in which post-provided face-plate of the shell or casing containing the catch-mechanism can be concealed by a cover-plate or 30 element pivotally connected with the said face-plate and adapted to be forced into its opened relation with the face-plate to permit the post-provided face-plate to be disengaged with a holding catch or latch-plate, or 35 to be engaged by said catch or latch-plate as the case may be.

The invention has for its further object to provide in connection with the shell or casing of the catch, a cover-plate which is 40 hinged to said shell or casing and is under the control of a normally operated spring, the said cover-plate being of any marginal configuration and any surface-ornamentation, or said cover-plate may serve as a 45 name-plate, or the like.

Other objects of the present invention not at this time more particularly enumerated will be clearly understood from the following detailed description of the present invention. 50

With the various objects of the present invention in view, the said invention consists in the novel locking or holding catch herein-after set forth; and, the invention consists, 55 furthermore, in the novel arrangements and

combinations of the several parts comprising the said catch, all of which will be more fully described in the following specification, and then finally embodied in the clauses of the claim which are appended to and 60 which form an esential part of said specification.

The invention is clearly illustrated in the accompanying drawings, in which:—

Figure 1 is a front view of a locking or 65 holding catch made according to and embodying the principles of the present invention, showing the catch in its position when securing the flap of a portfolio in its closed relation over the pocket or body of the portfolio, said view showing the cover-plate of the catch closed down upon the face-plate of the shell or casing of the catch; and Fig. 2 is a view of the devices shown in said Fig. 1, 70 with the cover-plate raised, the flap of the portfolio and its post-engaging catch being respectively shown in their detached or separated relation with the pocket or body of the portfolio and the face-plate of the catch or lock-casing or shell.

Fig. 3 is an end view of the locking or holding catch, detached from the pocket or body of the portfolio, said view being made on an enlarged scale, and the said cover-plate being shown closed down upon the 85 face-plate of the shell or casing of the locking or holding catch; and Fig. 4 is a rear view of the same.

Fig. 5 is a transverse vertical section of the catch, the cover-plate being represented 90 closed down upon the face-plate of the shell or casing of the locking or holding catch; and Fig. 6 is a similar sectional representation of the locking or holding catch, the cover-plate, however, being shown in its 95 opened or raised position.

Similar characters of reference are employed in the said above described views, to indicate corresponding parts.

Referring now to the said figures of the 100 drawings, the reference-character 1 indicates the main body or pocket-portion of a portfolio, or the like, and 2 is the usual flap connected in the usual manner with the said body or pocket-portion and which is to be 105 folded over the open portion or mouth of the said pocket or body. Suitably secured, in the proper place, to the marginal edge-portion of said flap is a suitably constructed catch or latch-plate, as 3; provided in this 110

case with a pair of post-receiving perforations or openings, as 4.

Referring now more particularly to the main holding or locking catch, illustrated as to its construction more especially in Figs. 3 to 6 inclusive, the same consists, essentially, of a main shell or casing comprising a face-plate 5, preferably of rectangular configuration, and formed with rearwardly projecting and longitudinal extending side-walls 6 and rearwardly projecting and laterally extending end-walls 7, the several walls being provided with marginal fastening lugs or extensions, as 8, for securing said shell or casing in its proper position upon the main body or pocket-portion of the portfolio, or the like. Other securing or fastening means may, however, be employed, if desired.

As shown, the said end-walls 7 are each provided at points near the said side-walls 6 with pintles 9 with which are pivotally suitably formed pivot-lugs or ears 11 which extend, at the proper location, rearwardly from the marginal edge-portions of a cover-plate 10, said plate conforming to the general marginal configuration of the face-plate 5 of the main shell or casing. Extending rearwardly from the said cover-plate 10 is a lever-engaging post or lug 12, formed with a nosing or engaging member 13. The said cover-plate 10 is also provided with a rearwardly extending spring-engaging post or lug 14, said post or lug 12 being adapted to enter an opening or perforation 15 in said face-plate 5, and the post or lug 14 being adapted to enter an opening or perforation 16, also in said face-plate 5. Extending from the outer face of the said face-plate 5 are a pair of retaining posts or lugs 17 of such lengths that the said posts or lugs will act as stops to limit the closing action of the cover-plate 10 and thereby provide a space, as 18, between the cover-plate 10 and the face-plate 5 for the reception of the edge-portion of the flap 2 and its catch or latch plate 3 in said space, and to permit of the entrance of the retaining posts or lugs 17 in the post-receiving perforations or openings 4 of said plate 3, to retain the flat 2 in its closed relation over the mouth or opening of the pocket of the portfolio, as will be clearly evident.

Movably disposed within the chambered portion of the shell or casing of the main holding or locking catch is a lever or arm 19 formed at one end with an angularly bent portion of such resiliency so as to provide a spring-member 20, the free end-portion 21 is fixed by being suitably secured upon the inner face of the face-plate 5 in any manner. As shown, the marginal edge-portion of the said lever or arm 19, normally extends partially across the opening 15 in the face-plate 5, for holding engagement with the nosing or

engaging member 13 of the lever or arm-engaging post or lug 12 when the cover-plate 10 is closed down over the said face-plate 5. The said lever or arm 19 is also of such length that its end-portion 22 projects into and from an elongated opening 23 in the corresponding end-wall 7 of the said shell or casing, said end-portion 22 being movably disposed in said opening 23, and being preferably provided, upon the outside of said shell or casing with a suitably shaped fingerpiece, as 24. Also secured within the chambered portion of said shell or casing, by means of a rivet 25, or other suitable fastening means, is a flat spring 26, said spring curving rearwardly and crossing over the back of the said lever or arm 19, and also having its end-portion 27 in forwardly pressing contact, normally, with the end-portion of the previously mentioned spring-engaging post or lug 14; substantially as shown in Fig. 5 of the drawings.

The operation of the device will be clearly understood from an inspection of the several figures of the drawings, it being evident that when the fingerpiece 24 is moved in the direction of the arrow in either Figs. 1, 3 or 4, the arm or lever 19 is withdrawn from its holding engagement with the nosing 13 of the post or lug 12, whereby the pressure of the spring 26 upon the end of the post or lug 14 will force the cover-plate 10 into its raised position indicated in Figs. 2 and 6 of the drawings. The catch-plate 3 can thereupon be removed from its retained engagement with the posts or studs 17, and the flap 3 brought into its separated and opened relation with the pocket or body of the portfolio. As soon as the pressure is removed from the fingerpiece 24, the action of the spring-member 20 returns the said arm or lever to its normal position, so that when the flap 3 is returned into its closing relation with the pocket or body 1, the cover-plate can once more be snapped into its covering position directly over the face-plate 5 of the shell or casing of the main holding or locking catch.

If desired, the said cover-plate 10 may be provided with a marginal projection 28, or similar means, adapted to contact with the side-wall 6, thereby acting as a stop which will limit the outward or raised movement of the said cover-plate, as will be clearly evident from an inspection of Figs. 3, 5 and 6 of the drawings.

From the foregoing description of the present invention it will be clearly evident, that I have devised a simply constructed and neat locking or holding catch with which the catch-plate upon the flap of a portfolio or the like can be brought into holding engagement, the two main members, when the cover-plate is closed down, being retained in their positively latched engage-

ment, and the said cover-plate serving at the same time as a means for inscribing thereon the name and address of the owner of the portfolio, or for the application 5 thereon of any other means of identification.

I claim:—

1. A catch for portfolios, and the like, comprising a main casing adapted to contain a cover-plate actuating mechanism, means connected with the said casing for engagement therewith of a latch-plate, and a cover-plate pivotally connected with said casing and coöperating with the actuating 15 mechanism thereof to conceal the said latch-plate.

2. A catch for portfolios, and the like, comprising a main casing adapted to contain a cover-plate actuating mechanism, 20 latch-plate engaging posts extending from said casing, and a cover-plate pivotally connected with said casing and coöperating with the mechanism thereof to conceal the said latch-plate.

25 3. A catch for portfolios, and the like, comprising a main casing adapted to contain a cover-plate actuating mechanism, means connected with the said casing for engagement therewith of a latch-plate, a cover-plate pivotally connected with said casing and coöperating with the actuating mechanism thereof to conceal the said latch-plate, and a stop-means connected with said cover-plate to limit the outward movement of the 30 same.

4. A catch for portfolios, and the like, comprising a main casing adapted to contain a cover-plate actuating mechanism, latch-plate engaging posts extending from said 40 casing, a cover-plate pivotally connected with said casing and coöperating with the mechanism thereof to conceal the said latch-plate, and a stop-means connected with said cover-plate to limit the outward movement 45 of the same.

5. A catch for portfolios, and the like, comprising a main casing consisting of a face-plate, side-walls and end-walls, one of said walls being provided with an opening 50 and the said face-plate being provided with a pair of post-receiving openings, means connected with said face-plate for engagement therewith of a latch-plate, a cover-plate pivotally connected with said casing, a lock-post extending from said cover-plate into and through one of the openings in the said face-plate, a spring-engaging post also extending from said cover-plate into and through the other opening in said face-plate, 55 a resilient post-engaging lever within said casing having a portion normally in engagement with said lock-post, said lever having another portion extending into and through the opening in the wall of said casing, said projecting portion of the lever 60 serving as a fingerpiece, and a spring-plate also within said casing, said spring-plate having a portion in engagement with said spring-engaging post.

serving as a fingerpiece, and a spring-plate also within said casing, said spring-plate having a portion in engagement with said spring-engaging post.

6. A catch for portfolios, and the like, 70 comprising a main casing consisting of a face-plate, side-walls and end-walls, one of said walls being provided with an opening and the said face-plate being provided with a pair of post-receiving openings, means 75 connected with said face-plate for engagement therewith of a latch-plate, a cover-plate pivotally connected with said casing, a lock-post extending from said cover-plate into and through one of the openings in the said face-plate, a spring-engaging post also 80 extending from said cover-plate into and through the other opening in said face-plate, a resilient post-engaging lever within said casing having a portion normally in engagement with said lock-post, said lever having another portion extending into and through the opening in the wall of said casing, said projecting portion of the lever serving as a 85 fingerpiece, a spring-plate also within said casing, said spring-plate having a portion in engagement with said spring-engaging post, and a stop means connected with said cover-plate to limit the outward movement of the 90 same.

7. A catch for portfolios, and the like, comprising a main casing consisting of a face-plate, side-walls and end-walls, one of said walls being provided with an opening and the said face-plate being provided with a pair of post-receiving openings, latch-engaging posts extending from the face-plate of the casing, a cover-plate pivotally connected with said casing, a lock-post extending from said cover-plate into and through 100 one of the openings in said face-plate, a spring-engaging post also extending from said cover-plate into and through the other opening in said face-plate, a resilient post-engaging lever within said casing having a 105 portion normally in engagement with said lock-post, said lever having another portion extending into and through the opening in the wall of said casing, said projecting portion of the lever serving as a fingerpiece, 110 and a spring-plate also within said casing, said spring-plate having a portion in engagement with said spring-engaging post.

8. A catch for portfolios, and the like, comprising a main casing consisting of a face-plate, side-walls and end-walls, one of said walls being provided with an opening and the said face-plate being provided with a pair of post-receiving openings, latch-engaging posts extending from the face-plate 120 of the casing, a cover-plate pivotally connected with said casing, a lock-post extending from said cover-plate into and through one of the openings in said face-plate, a spring-engaging post also extending from 125

said cover-plate into and through the other opening in said face-plate, a resilient post-engaging lever within said casing having a portion normally in engagement with said lock-post, said lever having another portion extending into and through the opening in the wall of said casing, said projecting portion of the lever serving as a fingerpiece, a spring-plate also within said casing, said 10 spring-plate having a portion in engage-

ment with said spring-engaging post, and a stop-means connected with said cover-plate to limit the outward movement of the same.

In testimony, that I claim the invention 15 set forth above I have hereunto set my hand this 7th day of February, 1918.

ROBERT O. FLOCKE.
